HYDROTHERAPEUTIC MASSAGE UNIT

Edwin F. Clements, 680 Alexander Way,
Palm Springs, Calif. 92262

Filed Dec. 13, 1965, Ser. No. 162

Term of patent 14 years

(Cl. D83—1)

FIG. 1 is a side elevation of a hydrotherapeutic massage unit, showing my new design, the opposite side having the same appearance.

FIG. 2 is an enlarged bottom plan thereof, rotated 90° from the position of FIG. 1.

FIG. 3 is a view partially shown in section taken on line 3—3 of FIG. 2.

I claim:

The ornamental design for a hydrotherapeutic massage unit, as shown and described.
